CLAIM

The ornamental design for an inflatable obstacle course, as shown and described.

DESCRIPTION

FIG. 1 is a perspective view of an inflatable obstacle course showing my new design;

FIG. 2 is a side view of the inflatable obstacle course of FIG. 1;

FIG. 3 is a top plan view of the inflatable obstacle course of FIG. 1;

FIG. 4 is a front view thereof of the inflatable obstacle course of FIG. 1;

FIG. 5 is a rear view thereof of the inflatable obstacle course of FIG. 1;

FIG. 6 is a cross-sectional view of the inflatable obstacle course along line 6-6 of FIG. 1;

FIG. 7 is a cross-sectional view of the inflatable obstacle course along line 7-7 of FIG. 1;

FIG. 8 is a cross-sectional view of the inflatable obstacle course along line 8-8 of FIG. 1; and,

FIG. 9 is a cross-sectional view of the inflatable obstacle course along line 9-9 of FIG. 1.
